SCHUYLER SCHIEFFELIN, OF NEW YORK, N. Y.

INTERNAL-COMBUSTION MOTOR.

Application filed June 11, 1925. Serial No. 36,497.

This invention relates to motors and has particular reference to certain improvements in the general construction and arrangement of the elements of an internal combustion motor.

In the common accepted forms of standard internal combustion motors, use is made of a cylinder with a reciprocating piston therein, a crank shaft and a connecting rod for transmitting rotary motion to the crank shaft, together with intake and exhaust valves controlled by a cam shaft operated from the crank shaft.

The present invention contemplates the simplification of the construction of a motor of the character set forth by the reduction to a minimum of the number of working parts by the elimination of crank shafts, connecting rods, pocket valves, and valve-operating means.

The present invention aims for some of its principal objects to eliminate all reciprocating parts except the pistons; to provide pistons which are detached from the other elements of the motor except for a driving connection with the drive shaft; to provide a motor from which side thrust, piping, or vibration is practically eliminated; to provide a motor in which acceleration is theoretically perfect; to provide fuel conduits from which angles which tend to impede the passage of the fuel, are absent, thereby permitting a straight flow; to provide a fluid-cooled motor in which the use of a pump is dispensed with and the flow of the fluid is effected by centrifugal force; and to provide a motor in which the adjustment for compensating for wear may be readily had and this while the motor is running.

The invention furthermore comprehends the production of an internal combustion motor in which the cost, weight, size and friction are greatly reduced, and in which the general efficiency is greatly increased.

With the above recited and other objects in view, reference is had to the following specification and drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a longitudinal sectional view through a motor constructed in accordance with the invention;

Fig. 2 is a plan view thereof; 60

Fig. 3 is a cross sectional view on an enlarged scale;

Fig. 4 is a fragmentary sectional plan view of the piston, illustrating the driving connection between the same and the drive 65 shaft;

Fig. 5 is a transverse sectional view illustrating the valve, and

Fig. 6 is a perspective view of one of the valves. 70

Referring to the drawings, the motor illustrated is of the two-cylinder type, it, however, being understood that the same may be made up of one or more cylinders without in any way departing from the spirit or 75 scope of the invention. In the drawings, 10 and 11 designate the sections of each cylinder, which are provided with flanged open inner ends 12 adapted to be bolted or otherwise secured together by bolts or fastening elements 13. Each cylinder section is provided with an outer closed cylinder head 14 having therein circumferentially spaced substantially sector-shaped intake and exhaust ports 15 and 16. A drive shaft 17 extends axially through the cylinder or through the several cylinders where more than one are employed, the same having a bearing in the cylinder heads. A piston having piston heads 19 and 20 on its opposite 80 ends, is mounted for both reciprocating and turning movements in each cylinder, and defines between said piston heads, the opposite ends of the cylinder and the cylinder heads, combustion chambers 21 and 22. The piston of each cylinder is splined to the drive shaft through the medium of a transverse key 23, which passes through a transverse opening in the drive shaft, with the outer terminals slidably engaging slots 24 in the 85 connecting webs 25 of the piston heads 19 and 20. The pistons 18, which are preferably of cylindrical construction, are provided with a circumferential continuous, sinuous or helical groove 26 having inwardly beveled 90 opposite walls 27. At diametrically opposite points, the cylinders at the juncture of their sections 10 and 11 have mounted in the guideways 28, a rotatably adjustable carrier 29. A pair of tapered abutment roll- 95

connecting webs 25 of the piston heads 19 and 20. The pistons 18, which are preferably of cylindrical construction, are provided with a circumferential continuous, sinuous or helical groove 26 having inwardly beveled 100 opposite walls 27. At diametrically opposite points, the cylinders at the juncture of their sections 10 and 11 have mounted in the guideways 28, a rotatably adjustable carrier 29. A pair of tapered abutment roll- 105

connecting webs 25 of the piston heads 19 and 20. The pistons 18, which are preferably of cylindrical construction, are provided with a circumferential continuous, sinuous or helical groove 26 having inwardly beveled 110 opposite walls 27. At diametrically opposite points, the cylinders at the juncture of their sections 10 and 11 have mounted in the guideways 28, a rotatably adjustable carrier 29. A pair of tapered abutment roll-

ers 30 are mounted on the carrier 29 for engaging within the sinuous or helical groove 26, whereby each reciprocation of the piston imparts thereto a rotary motion for turning or rotating the drive shaft with the piston. The carrier members 29 are adjusted by means of a jack screw 31, which threadingly engages a cover plate 32 for the guideways 28, and a binding nut 33 is employed for maintaining each carrier in its adjusted position. The intake and exhaust ports 15 and 16 are connected and communicate with the intake and exhaust manifolds or conduits 34 and 35.

Secured to the drive shaft 17 for turning movement therewith and mounted within the cylinder in snug contact with the inner wall of the cylinder head, are valve disks 36, each of which is provided with a single port 37 adapted upon rotation to respectively register with the intake and exhaust ports. Ignition or spark plugs 38 extend into each combustion chamber 21 and 22 for igniting the charge of fuel whereby to alternately reciprocate the piston in opposite directions.

The spacing of the intake and exhaust ports is such that after the port 37 of the valve has established communication between the intake manifold and the combustion chamber, the piston moving in a direction away from the cylinder head, will have drawn in a charge of fuel; the disk valve then cuts off communication so that the next stroke of the piston toward the cylinder head will compress the charge after which the ignition of the charge effects the power stroke of the piston in a direction away from the cylinder head. The next stroke of the piston toward the cylinder head causes the burnt gases to exhaust through the exhaust manifold, due to the fact that the port 37 of the disk valve registers with the exhaust port 16, after which the intake of the charge of fuel follows. As the charge is being ignited in one end of the cylinder and the piston being moved in a direction away from the cylinder head, the opposite piston head will be moved toward the cylinder head to exhaust the previously spent charge. Likewise the next stroke in the opposite direction will be drawing in a fresh charge while the previously ignited charge is exhausted in the opposite end, and, subsequently, on the next stroke the intake of the charge will be compressed while a fresh charge will be drawn in the opposite end and compressed by the ignition and explosion of the charge at the opposite end. It is preferable to employ at least two pairs of cylinders in order that each stroke of the piston will be partially effected by the explosion.

In order to provide means for cooling and lubricating the working parts of the motor, an oil radiator 40 is provided, which is con-

nected by a feed pipe 41 to an axial feed opening 42 in the drive shaft. The feed opening 42 leads through the radial branches 43 to the radial openings 44 in a collar 45 secured to and rotatable with the shaft by the passage of the key 23 therethrough and the securement of the key by a bolt or other fastening element 46. The radial aligned openings 43 and 44 constitute when the shaft is rapidly rotating, means for centrifugally discharging the oil from the oil radiator 40 into the interior of the piston for cooling the same, and, at the same time, applying lubricant to the engaging faces of the abutment rollers 30 and the groove 26, while supplying the necessary lubricant to the outer walls of the piston and inner walls of the cylinder. The excess oil, due to the centrifugal force, is thrown outwardly through the groove or slot 26, and through an opening 47 covered by an oil-return pipe 48, which leads back to the oil radiator after passing through a strainer screen 49. If desired, as illustrated, an air inlet nozzle or hood 50 may be provided and disposed in a direction to cause a circulation of air within the piston.

I claim:—

1. In an internal combustion motor, a cylinder, a piston mounted therein for reciprocation, interengaging means on the cylinder and piston for effecting rotary motion therebetween during the reciprocations of the piston, and a drive shaft extending axially through the cylinder and piston, having splined connection with the piston, the said cylinder having cylindrical heads at its opposite ends, each provided with circumferentially spaced intake and exhaust ports and disk valves keyed to the drive shaft, disposed within the cylinder heads, each disk valve having a single port therein adapted to register with the intake ports during the inward movement of the pistons, to be disposed in a non-registering position with the cylinder head ports during the succeeding outward and inward strokes and adapted to register with the exhaust port during the succeeding outward stroke.

2. The combination with an internal combustion engine including a cylinder, a piston mounted therein for reciprocation, means for effecting relative rotary motion between the piston and cylinder during the reciprocations of said piston, and a drive shaft adapted to rotate with the piston; of means for effecting reciprocations of the piston, comprising cylinder heads at the opposite ends of the cylinder having circumferentially spaced intake and exhaust ports, valve disks secured to the drive shaft and each provided with a single opening constituting a combined intake and exhaust port adapted to initially register with the cylinder head intake port during the inward movement of

- the piston to effect the introduction of a charge into the cylinder, adapted to be disposed out of registry with the cylinder head ports during the succeeding outward stroke 5 of the piston to effect the compression of the charge, adapted to be disposed out of registry with the cylinder head ports during the succeeding inward stroke of the piston under the explosive action of the charge, and 10 adapted to register with the exhaust port of the cylinder head during the following outward stroke of the piston to exhaust the charge.
3. The combination with an internal combustion engine including a cylinder, a piston mounted therein for reciprocation, means for effecting relative rotary motion between the piston and cylinder during the reciprocations of said piston, and a drive shaft 15 adapted to rotate with the piston; of means for effecting reciprocations of the piston, comprising cylinder heads at the opposite ends of the cylinder having circumferentially spaced intake and exhaust ports, valve 20 disks secured to the drive shaft and each provided with a single opening constituting a combined intake and exhaust port adapted to initially register with the cylinder head intake port during the inward movement of 25 the piston to effect the introduction of a charge into the cylinder, adapted to be disposed out of registry with the cylinder head ports during the succeeding outward stroke of the piston to effect the compression of the 30 charge, adapted to be disposed out of registry with the cylinder head ports during the succeeding inward stroke of the piston under the explosive action of the charge, and adapted to register with the exhaust port of 35 the cylinder head during the following outward stroke of the piston to exhaust the charge, the opposite ends of the piston and the disk valves being correlated in such a 40 manner that the combustion between one cylinder head and one end of the piston functions alternately to set up a compression of the charge between the opposite cylinder head and the opposite end of the piston and the exhaustion of the spent gases from there- 45 between.
4. An internal combustion motor, comprising a pair of cylinders each having a closed end constituting a cylinder head provided with circumferentially spaced intake 50 and exhaust ports, the opposite open end being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 55 the abutments upon reciprocation of the piston to effect rotation thereof and turning movement of the shaft, the groove and abutments having tapered walls, and means for moving the abutments relative to the groove to take up wear thereon.
5. An internal combustion motor, comprising a pair of cylinders each having a closed end constituting a cylinder head provided with circumferentially spaced intake 60 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 65 the abutments upon reciprocation of the piston to effect rotation thereof and turning movement of the shaft, the groove and abutments having tapered walls, and means for moving the abutments relative to the groove to take up wear thereon.
6. An internal combustion motor, comprising a pair of cylinders each having a closed end constituting a cylinder head provided with circumferentially spaced intake 70 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 75 the abutments upon reciprocation of the piston to effect rotation thereof and turning movement of the shaft, the groove and abutments having tapered walls, and means for moving the abutments relative to the groove to take up wear thereon.
7. An internal combustion motor, comprising a pair of cylinders each having a closed end constituting a cylinder head provided with circumferentially spaced intake 80 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 85 the abutments upon reciprocation of the piston to effect rotation thereof and turning movement of the shaft, the groove and abutments having tapered walls, and means for moving the abutments relative to the groove to take up wear thereon.
8. An internal combustion motor, comprising a pair of cylinders each having a closed end constituting a cylinder head provided with circumferentially spaced intake 90 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 95 the abutments upon reciprocation of the piston to effect rotation thereof and turning movement of the shaft, the groove and abutments having tapered walls, and means for moving the abutments relative to the groove to take up wear thereon.
9. An internal combustion motor, comprising a pair of cylinders each having a closed end constituting a cylinder head provided with circumferentially spaced intake 100 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 105 the abutments upon reciprocation of the piston to effect rotation thereof and turning movement of the shaft, the groove and abutments having tapered walls, and means for moving the abutments relative to the groove to take up wear thereon.
10. An internal combustion motor, comprising a pair of cylinders each having a closed end constituting a cylinder head provided with circumferentially spaced intake 110 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 115 the abutments upon reciprocation of the piston to effect rotation thereof and turning movement of the shaft, the groove and abutments having tapered walls, and means for moving the abutments relative to the groove to take up wear thereon.
11. An internal combustion motor, comprising a pair of cylinders each having a closed end constituting a cylinder head provided with circumferentially spaced intake 120 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 125 the abutments upon reciprocation of the piston to effect rotation thereof and turning movement of the shaft, the groove and abutments having tapered walls, and means for moving the abutments relative to the groove to take up wear thereon.
12. An internal combustion motor, comprising a pair of cylinders each having a closed end constituting a cylinder head provided with circumferentially spaced intake 130 and exhaust ports, the opposite open ends being disposed in confronting relation and in axial alinement and formed with diametrically opposed inwardly projecting abutments, a double-ended piston having its opposite ends mounted, respectively, within the cylinders for reciprocation and rotary movement, a shaft passing axially through the cylinders and splined to the piston for rotation therewith, a circumferentially helical groove in said piston co-operating with 135 the abutments upon reciprocation of the piston to effect rotation thereof and turning movement of the shaft, the groove and abutments having tapered walls, and means for moving the abutments relative to the groove to take up wear thereon.

said motor, comprising a cooling fluid radiator having an intake conduit communicating with the interior of the piston, the said shaft having a fluid feed port extending axially therethrough and radially therefrom within the piston and a fluid feed conduit leading from said radiator to the fluid feed port of the shaft, the rotation of the shaft setting up a centrifugal action for drawing the fluid through the shaft port, ¹⁰ expelling the same against the interior of the piston, and discharging the same through the intake conduit to the fluid radiator.
